(57) **CLAIM**

The ornamental design for a magnetic building block, as shown and described.

DESCRIPTION

FIG. 1 is a front, left and bottom perspective view of a magnetic building block, showing my new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view of the magnetic building block combined with an unclaimed cover.

The broken lines shown in the drawings illustrate portions of the magnetic building block that form no part of the claimed design.
